FIG. 3.

FIG. 4.

FIG. 5.

INVENTOR
Henry E. Leppert,

BY
H. E. Leppert
ATTORNEY

UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed June 27, 1923. Serial No. 571,307.

To all whom it may concern:

Be it known that I, HENRY E. LEPPERT, a citizen of the United States of America, residing at New Britain, Connecticut, have invented a new and useful Electric Switch, of which the following is a specification.

My invention relates particularly to what are commonly termed wall switches. The main object is to provide convenient means 10 for grounding the frame of the switch.

Another object is to provide a convenient and neat method of positioning the parts of a toggle or lever switch in a face plate.

Fig. 1 is a side view and partial section 15 of a toggle switch embodying the improvements of my invention.

Fig. 2 is a front view of the same.

Fig. 3 is a perspective view showing the various novel elements of my invention.

Fig. 4 is a side view and partial section 20 of parts of the invention.

Fig. 5 is a plan view and partial section on the plane of the line 5—5 of Fig. 4.

Such switches are usually provided with 25 an insulating body or receptacle 7 and a face plate 8. A switch mechanism which may be of any suitable form is carried in some suitable manner by the supporting frame 9. A movable element 10 of the switch mechanism 30 is shown in Fig. 5.

The handle or operating lever 11 may be connected to the switch mechanism in any suitable manner, such lever being pivotally carried for instance in ears 12—12 of the 35 frame 9.

A ring 13 is secured for instance by means 40 of lugs 14 to the front of the frame 9. This ring has a central opening 15 to permit it to be slipped on over the handle 11. A split cover piece 16 is adapted to be slipped on over the shank of the handle 11 and it is 45 preferably provided with a boss 17 adapted to fill in the sides of the opening 15. The ring 13 is adapted to fit in the opening 18 of the face plate 8 so as to give an attractive 50 finish when the parts are assembled.

A yoke 19 affords seats for screws 20 which hold the face plate in place. This yoke has a central opening 21 adapted to receive the 55 ring 13. Preferably the edges of this opening are roughened or provided with teeth 22 so as to furnish a sharp means of connection with the ring 13 and thus efficiently electrically connect the switch frame 12 with the

face plate 8. The arms of the yoke may be 55 split or slotted as at 23 so as to enable the central part of the yoke to expand or give when the yoke is applied to the ring 13 and thus effect a snug connection between the two parts. 60

While I have thus far described a preferred form of construction, it should be obvious that I contemplate that changes may be made and even that parts such as the cover piece 16 may be omitted and that parts may 65 be combined without departing from the spirit or scope of my invention.

When the lever 11 is pivoted in the frame 9 the piece 16 may be readily slipped in place and then the ring 13 applied and the lugs 14 70 bent over. When the yoke 19 is applied the jaws 22 yield and slide on over the ring 13 establishing an intimate contact therewith and thence to the face plate 8 when that is in place. 75

The switch mechanism is preferably assembled as a unit as is more clearly described in my co-pending application after which the cover piece 16 and the finished lacquered ring 13 may be added to the unit which is 80 then secured in position in the base.

The yoke 19 is then forced over the lacquered ring 13 and preferably twisted or turned so that the roughened edges or teeth of the yoke may cut through the lacquer on 85 the ring and establish an electrical grounding connection with the switch unit. The grounding circuit is completed by securing the switch in the usual metal box which is grounded by means of wire in the usual manner. 90

It is obvious that the cover plate 16 and the ring 13 may be polished and finished before assembling to the switch unit and will present a practically closed and finished construction when covered by the usual switch plate 8. 95

I claim:

1. In an electric switch, a frame, an operating lever pivoted thereto, a split cover 100 piece connected to said frame open at one end and having arms at the sides of said lever, a face-plate and means for electrically connecting said face plate and said cover piece. 105

2. In an electric switch, an insulating housing, a switch frame mounted therein, an operating member mounted in said frame,

a cover member surrounding said operating member and a split yoke yieldingly and electrically connected to said cover member.

3. In an electric switch, an insulating housing, a switch frame mounted therein, an operating member mounted in said frame, a cover member surrounding said operating member, a split yoke yieldingly connected to said cover member and a face plate electrically connected to said yoke.

4. In an electric switch, a housing, a switch frame mounted therein, an operating member, a ring surrounding said operating member, and a yoke having teeth yieldingly engaging said ring.

5. In an electric switch, an insulating housing, a switch frame secured thereto, an operating lever, a cover ring surrounding said lever, and a resilient yoke detachably embracing said ring.

6. In an electric switch, a frame, an operating lever carried thereby, a slotted cover piece at the side of said lever, a ring holding said cover piece in place, a yoke yieldingly engaging said ring and a face plate connected to said yoke.

7. In an electric switch, a frame, an operating lever, a slotted cover piece on said lever and having a boss, a ring surrounding said lever and embracing said boss.

8. In an electric switch, a frame, an operating lever, a cover piece on said lever and having a boss, a ring surrounding said

lever and embracing said boss and a yoke yieldingly electrically engaging said ring.

9. In an electric switch, a frame, an operating member carried thereby, a ring embracing said member and a split yoke having teeth engaging said ring.

10. In an electric switch, a frame, a pivoted lever, a resilient split yoke, and means interposed between said yoke and said frame for grounding said frame through said yoke.

11. In a switch construction, an assembled frame and switch contacts and operating lever, a face plate ring having a central opening for said lever, and a forked plate having a boss at the sides of said lever in said opening.

12. In an electric switch, a frame having a front piece and lugs, a lever pivotally mounted in said lugs and extending through said front piece, a forked cover supported on said front piece with its arms at the sides of said lever and a face plate ring surrounding said forked cover and secured to said front piece.

13. As an article of manufacture, a yoke for connecting the insulating housing of a flush type switch to a front plate and having yielding side arms with sharp teeth for electrically engaging a metallic part of the switch mechanism and grounding the same to the face plate.

HENRY E. LEPPERT.
